UNITED STATES PATENT OFFICE.

GEORGE ZIMMERMAN, OF BATTLE CREEK, NEBRASKA.

STOCK-WATERER.

1,162,539.

Specification of Letters Patent. Patented Nov. 30, 1915.

Application filed July 17, 1912. Serial No. 709,997.

To all whom it may concern:

Be it known that I, GEORGE ZIMMERMAN, a citizen of the United States, residing at Battle Creek, in the county of Madison, 5 State of Nebraska, have invented certain new and useful Improvements in Stock-Waterers; and I do hereby declare the following to be a full, clear, and exact description of the invention, such as will enable others 10 skilled in the art to which it appertains to make and use the same.

This invention relates to watering devices and more particularly to that class known as stock waterers.

15 The object of the invention is to provide a stock waterer which will be of simple construction and sanitary in use the trough thereof being secured in such manner that it may be readily swung upon hinges for 20 cleansing the same but when in position for use will be securely held in place.

In the drawings:—Figure 1 is a view of the top portion of the device in position for use. Fig. 2 is a vertical longitudinal view 25 through the complete device. Fig. 3 is a horizontal sectional view on the line 3—3 of Fig. 2. Fig. 4 is a vertical sectional view on the line 4—4 of Fig. 2.

Referring more specifically to the drawings, in which similar reference numerals 30 designate corresponding parts throughout, 10 indicates the reservoir having hinged to the upper edge of one end, the trough 11, said trough being hinged thereto along its 35 upper edge and adapted to normally rest within the adjacent end of said reservoir.

The reservoir 10 is provided with the cover 12 hinged to the upper edge of the end opposite that to which the trough 11 is connected, the cover 12 extending a short distance over the edge 11' of the trough when said cover is in closed position, thus preventing the stock from moving the trough. The trough 11 is provided with the inlet opening 40 45 13 near the upper edge 11' thereof, to permit water from the reservoir 10 to enter the trough.

The reservoir 10 is provided in its rear end with the supply pipe opening 14 and a 50 second supply pipe opening 15 in the bottom thereof adjacent said rear end, either one of which may be employed to accommodate the supply pipe 16 while the other opening is closed by suitable plugs 17, as will be clearly 55 apparent. I have shown in Figs. 1 to 4 in-

clusive, the supply pipe 16 being secured in the opening in the bottom of the reservoir while the other opening 15 has the plug 17 positioned therein but it will be apparent that the arrangement of the supply pipe 16 and plug 17 may be reversed should occasion require.

The threaded end of the supply pipe 16 is shown extending into the reservoir and secured around this end is the valve seat 18 to 65 the upper face of which are secured the lower ends of the valve supporting legs 19, which lower ends are bent downwardly at right angles to the main portion of said legs. Positioned through the central opening 20 in the main portion of the legs 19, is the 70 valve stem 21 carrying the valve 22 upon its lower end which is resiliently held away from the valve seat 18 and against the underside of the legs 19, by means of the coil 75 spring 23 positioned around the stem above said legs 19 and bearing against the latter and against the head 24 and the upper end of the stem 20. This permits of a free flow of water into the reservoir even though the 80 water pressure is low.

Secured to the bottom of the reservoir 10, is the horizontal leg 25 of an L-shaped bracket, from the upper end of the upwardly extending arm 26 of which projects the pin 85 27 which extends in a horizontal direction and transversely of the reservoir. The L-shaped bracket serves to support the valve controlling mechanism which is suspended upon the pin 27, as will now be fully described.

The valve controlling mechanism consists of a horizontal rod 28 having its rear end inclined downwardly as shown at 29 and then directed upwardly as shown at 30 for 95 purposes to be presently explained while the float 31 is adjustably secured through the forward end thereof, the stem 32 projecting downwardly from the float 31 being passed through one of the series of openings 33 within said rod 28 and adjustably held in 100 position by means of the nuts 34 threaded upon said stem and engaged against opposite faces of the rod. The horizontal rod 28 is bowed about midway its length, as 105 shown at 35, which bowed portion is engaged over the pin 27 and the oppositely curved strap 36 is secured to the bowed portion 35. The strap 36 lies beneath the pin 27 and limits the longitudinal movement of the 110

rod 28 upon said pin without interfering with the pivotal movement of said rod. It will be understood that the pin 27 is provided with a suitable head 37 upon its outer end to prevent the rod 28 working off of said pin.

When the valve is engaged over the pipe 16 and the latter secured in the bottom of the reservoir, the portion of the horizontal rod 28 between the bowed portion and the inclined portion 29, engages the head 24 of the valve stem 20 and thus forces the valve 22 toward the valve seat 18 as the float 31 rises, thus cutting off a supply of water to the reservoir. Upon downward movement of the float 31, however, the spring 23 draws the valve 20 away from the seat 18, as will be clearly apparent.

With the above described construction, it will be apparent that when desired the plug 17 may be removed from the end of the reservoir and the pipe 16 engaged in place of it with its valve and accompanying parts, the plug being substituted in turn for the pipe 16. In this position of the valve, it will be engaged by the upturned end portion 30 of the rod 28 to hold the valve closed

when the float rises with the water in the reservoir to the desired height.

What I claim is:—

In a stock waterer, a reservoir, a tank positioned in one end of the reservoir and having the inner end of its wall provided with an inlet opening and further having its bottom normally engaged with the bottom of the reservoir, upstanding ears on the sides of the tank, said ears pivoted to the reservoir whereby the tank can be raised and swung from engagement with the reservoir, a supply pipe positioned in the other end of the reservoir, a valve and valve controlling mechanism within the reservoir for regulating the supply of water thereto, and a cover for the reservoir pivoted to the end of the reservoir opposite the tank, said cover extending to a point to overlap the inner end of the tank.

In testimony whereof, I affix my signature, in presence of two witnesses.

GEORGE ZIMMERMAN.
